UNITED STATES PATENT OFFICE.

EMILE REYSSIER, OF NEW YORK, N. Y., AND CHARLES G. GOTTSCHALK,
OF JERSEY CITY, NEW JERSEY.

DESIGN FOR A GLOVE.

SPECIFICATION forming part of Design No. 14,588, dated January 29, 1884.

Application filed November 27, 1883. Term of patent 3½ years.

To all whom it may concern:

Be it known that we, EMILE REYSSIER, a citizen of the United States, residing at New York city, and CHARLES GODFREY GOTTS-
5 CHALK, a citizen of the Republic of France, residing at Jersey City, New Jersey, have invented and produced a new and original Design for Gloves, of which the following is a specification, reference being had to the accompanying drawing, forming part thereof.

Heretofore gloves have been made with gauntlets of various forms and configuration, the gauntlet having been so formed as to open at one side.

15 The leading feature of the design herein is a glove, A, of the pattern made with a closed top, with the exception of a short opening at the wrist to be closed by buttons or other fastening, to which is attached a closed gauntlet,

B, or one made in the form of a cylinder or 20 cone-shaped—that is, continuous about the top of the glove. The gauntlet B is ornamented with grooves or channels indented thereon, dividing the surface into various blocks or sections of irregular form. 25

What we claim, and desire to secure by Letters Patent, is—

The design for a glove herein shown and described, consisting of a glove having a gauntlet ornamented on its surface by grooves or 30 channels into sections or blocks of irregular form, substantially as specified.

E. REYSSIER.
C. G. GOTTSCHALK.
